UNITED STATES PATENT OFFICE.

MORTIMER L. PACKER, OF COLUMBUS, OHIO.

FUEL MIXER.

1,420,277.

Specification of Letters Patent. Patented June 20, 1922.

Application filed August 15, 1921. Serial No. 492,599.

To all whom it may concern:

Be it known that MORTIMER L. PACKER, a citizen of the United States, residing at Columbus, in the county of Franklin and

5 State of Ohio, has invented certain new and useful Improvements in Fuel Mixers, of which the following is a specification.

This invention relates to improvements in gas burners and has for a primary object 10 to provide a gas burner, particularly of the type disclosed in my prior patent issued August 20, 1918, No. 1,276,257, by providing an improved adjustable air regulating shutter construction, the latter serving to permit 15 of a regulated intermingling of graduated quantities of a gaseous fuel with the oxygen of the atmosphere, in order that the burner may be adapted to variations in the flow rates of the fuel and to thereby permit of a 20 more efficient and economical consumption of the fuel.

Another object of the invention resides in providing a longitudinal fuel manifold with outwardly extending discharge tubes where- 25 in air admitting pores are provided, in surrounding said tubes with air regulating sleeves wherein pores are provided capable, upon the rotation of said sleeves, of being brought into registration more or less with 30 the pores provided in said tubes, whereby air may pass into said tubes and will be entrained and commingled with the fuel stream passing through said tubes for subsequent combustion and in providing means 35 whereby said sleeves may be manually ad- justed.

A further object of the invention rests in a burner wherein a plurality of mixing tubes are mounted in longitudinal array upon the 40 fuel manifold, in providing the air controlling shutters or sleeves of said tubes with laterally offset projections which are adapted to be pivotally connected with a longitudinally extending link member and in 45 connecting said link member with a man- ually operated lever which extends to a position where the same may be conveniently engaged for manual operation, the engage- ment being such that upon the oscillation of 50 said lever, said link member will be recip- rocated so as to effect simultaneous rota- tion on the part of said sleeves, thereby permitting of a uniform air adjustment to be made by a single operation in all of said 55 tubes so that the entire length of the burner will be rendered uniform in its operation.

For a further understanding of the invention, reference is to be had to the following description, and to the accompanying drawing, wherein:

Figure 1 is a perspective view of the im- 60 proved fuel commingling apparatus comprising the present invention, and

Figure 2 is a transverse vertical sectional view taken along the line 2—2 of Figure 1. 65

The burner or fuel commingling apparatus 1 disclosed in the accompanying drawing consists essentially of a longitudinally extending fuel manifold 2, into which gaseous fuel from any suitable source may 70 be appropriately introduced, one end of said manifold being closed by means of a cap 3. Arising from the manifold 2 at opposite ends thereof are spaced brackets 4, which serve to support a mixing reservoir 5, which 75 extends in parallelism with the manifold 2. The reservoir is provided at spaced longitudinal positions with vertically extending stationary supported tubes 6, which are so formed as to project into the space between 80 the reservoir and the manifold 2 and also upwardly into the reservoir and to be terminated in spaced relationship from the top wall of said reservoir. The tubes 6 have their lower ends formed with air admitting 85 pores 7, and the lower ends of said tubes are adapted to be surrounded by adjustable sleeves 8, which serve to regulate the pores 7 by governing their effective area. The sleeves 8 are formed with slots 9, which, 90 upon rotation of said sleeves, are capable of being moved into and out of registration with the pores 7 so as to govern the entrance of air into said tubes.

In this instance the manifold 2 is pro- 95 vided, in vertical alignment with the axes of the tube 6 with relatively short upwardly extending jets 10, which pass through open- 100 ings provided in the bottoms 11 of the sleeves 8, the said jets thereby being in com- munication with the interior of the tubes so that gas may directly pass into the latter, also, the said jets serving to provide, in con- junction with the lower ends of the tubes 6, vertical pivotal axis for the sleeves 8. 105 The bottoms 11 are provided with integral laterally projecting ears 12, to which a longi- tudinally extending actuating bar 13 is pivotally connected, the arrangement being such that upon the reciprocation of the bar 13, the said sleeves 8 will be simultaneously 110 and uniformly rotated so as to govern the in-

flow of air through the pores 7 and the slots 9. The bar may be actuated by means of a lever 14, which is pivoted as at 15 upon a stationary bar of a stove casing 16, and the 5 outer end of the lever projects through a slot 17 provided in the front wall of said casing. Obviously, by manipulating the outer end of the lever 14, the latter may be oscillated so as to impart sliding movement to the bar 13, thereby causing the 10 partial rotation of the air admitting sleeves or shutters 8, and the consequent control of the fuel mixture passing through the tube 6. This air adjustment has been found desirable in localities wherein the fuel pressure fluctuates to some considerable extent, 15 since by reason of the adjustment, the volume of air admitted into the tubes 6 may be readily controlled in accordance with the fuel pressure, so that the most efficient and economical results from the combustion of the fuel may be obtained at all pressures. It is in this respect mainly that the present invention differs from the construction 20 set forth and claimed in my prior patent above given, as it will be observed that in said patent the inflow of air into the said tubes is constant at all times, and irrespective of fluctuation in the fuel pressures, a 25 condition which does not permit at all times of efficient combustion. However, in the present invention the inflow of air may be easily and properly regulated, so as to insure proper combustion and to permit of 30 the inflow of air into the tubes in a manner proportionate to the volume of fuel passing through such tubes. This construction results in a material improvement upon the construction disclosed in my aforesaid patent. 35

It will be apparent that the air and fuel will flow through the tubes 6 and will be delivered into the reservoir 5. Then by the instrumentality of outlet tubes 18, the 40 commingled gas and air will be permitted to flow from the reservoir 5 in order that combustion thereof may be effected at the tips of the tubes 18. The tubes 18 are located in parts, one of which being located on each 45 side of each of the tubes 6, and the discharge ends of the tubes 6 are vertically spaced from the inlet ends of the tubes 18, a feature which results in causing the fuel stream to follow a circuitous path while passing 50 through the mixer and to thus insure a

thorough commingling of the fuel with the air.

What is claimed is:

1. A fuel commingling structure for gas burners, comprising a fuel supply pipe, a mixing receptacle disposed in cooperative relation with said pipe, an inlet member carried by said receptacle and situated so that one extremity thereof will be in alignment with an outlet opening formed in said pipe, the opposite end of said member extending into said receptacle, the lower end of said member being provided with an air inlet port, a manually operated shutter for controlling the effective area of said port, and discharge tubes carried by said reservoir and situated adjacent to said inlet member. 60

2. A fuel commingling structure for gas burners comprising a supply pipe having longitudinally spaced outlet openings formed therein, a reservoir situated above said pipe, a plurality of tubes having the lower ends thereof disposed for registration with said openings, said tubes having ports provided contiguous to the lower ends thereof and positioned between said supply pipe and reservoir, slotted sleeves rotatably mounted around the lower ends of said tubes and operable upon adjustment to control the effective area of said ports, and manually operated means for effecting simultaneous operation and uniform adjustment of said sleeves. 70

3. In a fuel mixer, a longitudinally extending supply pipe having spaced outlet openings formed therein, a longitudinally extending reservoir spaced from said pipe, tubes carried by said reservoir and having certain of the ends thereof arranged to project beyond said reservoir and into cooperation with the openings in the supply pipe, said tubes between said pipe and reservoir being provided with air ports, shutters movably associated with said tubes and arranged upon manual operation to control the effective area of said ports, ears projecting from said shutters, and a master bar pivotally uniting said ears and adapted upon reciprocation to simultaneously and uniformly adjust said shutters. 80

In testimony whereof I affix my signature.

MORTIMER L. PACKER.
